UNITED STATES PATENT OFFICE.

PAUL WUNDER, OF GLEN ULLIN, NORTH DAKOTA.

HORSESHOE.

1,222,708.

Specification of Letters Patent. Patented Apr. 17, 1917.

Application filed May 12, 1916. Serial No. 97,084.

To all whom it may concern:

Be it known that I, PAUL WUNDER, a subject of the Emperor of Germany, residing at Glen Ullin, in the county of Morton and 5 State of North Dakota, have invented certain new and useful Improvements in Horseshoes; and I do hereby declare the following to be a full, clear, and exact description of the invention, such as will enable others 10 skilled in the art to which it appertains to make and use the same.

This invention relates to new and useful improvements in horseshoes and more particularly to horseshoes having removable 15 calks thereby enabling the user to substitute sharp or blunt calks for use in slippery or dry weather.

Another object of the invention is to provide a horseshoe in which the calk may be 20 readily removed and replaced.

A further object of the invention is to provide a novel form of calk holder having transverse grooves for permitting of the insertion of a suitable instrument by which the 25 calk may be readily removed.

A still further object of the invention is to provide a novel form of calk having a suitable axial bore in the lower end thereof which is filled with cork or any other suitable 30 fibrous material for cushioning the calk.

With these and other objects in view, the invention consists in the novel combination and arrangement of parts which will be fully set forth in the following specification 35 and accompanying drawings, in which:—

Figure 1 is a bottom plan view of a horseshoe constructed in accordance with this invention showing one of the calks removed.

Fig. 2 is a side view in elevation of Fig. 1, 40 and

Fig. 3 is a sectional view on line 3—3 of Fig. 1.

Referring to the drawings the numeral 1 designates the body of the shoe which is substantially U-shaped as in the ordinary way and provided with the usual toe plate 2. The free ends of the arms of the shoe forming the heel portion thereof are provided 45 with suitable apertured bosses 3 forming heel plates as clearly shown in the drawings.

Formed in the toe plate 2 is a pair of transversely alining hexagonal openings 4 which are spaced equi-distant from the longitudinal axis of the shoe and are adapted 50 to receive the calk. These openings 4 ex-

tend from the under face of the toe plate 2 to the upper face of the toe of the shoe and taper so that the farther the tongue is driven thereinto the tighter it will be wedged. Extending transversely of the plate 2 and from its side edges inwardly toward the openings 4 are the grooves 5 which are adapted to accommodate a suitable instrument for the removal of the calk. Each of the openings 4 is provided with a pair of grooves which are arranged in opposition as clearly shown in Fig. 1.

The bosses 3 are each formed with tapered hexagonal openings similar to the openings 4 hereinbefore referred to which extend from the inner faces of the bosses through the upper face of the shoe and these bosses like the toe plates are formed with diametrically opposite transverse grooves which extend from the periphery of the bosses into the openings formed therein to allow for the insertion of an instrument by which the calk may be removed.

Passing now to the description of the calk reference will be had particularly to Figs. 2 and 3 which figures clearly illustrate the type of calk used in connection with the device and this calk is designated generally by the numeral 6 and comprises the cylindrical body 7 formed with a socket 8 extending from the lower end thereof well up into the body which socket is adapted to receive the calk or other cushion 9 as clearly shown in Fig. 3. A flange 10 is formed at the upper end of the body and extending upwardly from the flange is the upwardly tapering hexagonal stem 11 which is of a size to fit within the openings 4 and those in the bosses 3. It will thus be seen that the calks are interchangeable and the heel calks may be substituted for the toe calks and vice versa.

It will be apparent from the foregoing that in use the calks are driven firmly in place by forcing the tapered stem 11 into the openings 4 and when it is desired to change this calk it will be evident that a suitable instrument may be inserted in the slot 5 and engage the inner face of the flange 10 thereby allowing the instrument to force the calk from its position and permit of the easy removal thereof.

While in the foregoing there has been shown and described the preferred embodiment of this invention, it is to be understood that such changes may be made in the com-

bination and arrangement of parts as will fall within the spirit and scope of the appended claim.

What is claimed is:—

- 5 In a horseshoe, a body, a toe plate secured to the under side of the body, bosses formed on the heel of the body on the under side thereof, said toe plate and bosses being provided with tapered hexagonal shaped apertures and also having grooves in the under side thereof bisecting said apertures to admit an instrument for the removal of the calk, the calks being adapted to be attached to the shoe, tapered hexagonal shaped exten-
10 tions formed on the calks and adapted to be driven into the tapered hexagonal shaped apertures, flanges on the calks at the point
- 15

Copies of this patent may be obtained for five cents each, by addressing the "Commissioner of Patents, Washington, D. C."

where the extensions join the calks limiting the upward movement of said calks into the apertures of the body and also permitting 20 of the ready insertion of the instrument for the removal of the calks, said calks also being provided with axial bores and cushioning elements in said bores, said hexagonal shaped extensions of the calks preventing 25 rotation of the calks when inserted in the hexagonal shaped apertures of the body.

In testimony whereof I affix my signature in presence of two witnesses.

PAUL WUNDER.
